UNITED STATES PATENT OFFICE.

PAUL E. CARTER, OF BRONXVILLE, NEW YORK, ASSIGNOR TO GENERAL RAILWAY SIGNAL COMPANY, OF GATES, NEW YORK, A CORPORATION OF NEW YORK.

LIGHT SIGNAL.

Application filed November 9, 1921, Serial No. 514,053. Renewed September 27, 1927.

This invention relates to color light signals for railway signaling purposes.

The need of visibility of a signal at long range, the necessity of a wide spread of light and the advisability of keeping the energy consumption as low as possible, especially where the energy is derived from a primary battery, necessitates the use of an efficient light projecting unit. In the particular type of signal to which this invention relates, a suitable reflector is employed to make possible the utilization of as much of the spherical candle power as practicable. A reflector of this kind can not be used to best advantage directly behind a lens of a particular color for giving a certain signal, for if the lamp in such a reflector is put out so as not to give that particular signal, the light from the sun or a locomotive headlight directed into the signal casing may be reflected back and make it appear as though the light therein were illuminated, thereby giving a false signal. Consequently, a movable color screen should be used with a reflector, since if outside light is then reflected back, the proper signal indication will be given, the color of the light reflected back being that corresponding to the position of the color screen. In a sense a movable color screen makes the reflector advantageous rather than disadvantageous, in that, it would give the proper signal due to light entering the signal box from the outside, even though the lamp filament is burned out. In practice three indications are ordinarily required, that is, danger, caution and proceed. In many instances the control for these indications is obtained from a polarized circuit and relay, and the color screen is shifted by a polarized three-position relay movement. In order to have an arrangement to operate on the side of safety, it is desirable to give a danger indication when the relay is deenergized, the caution indication when the relay is energized with one polarity, and the clear indication for the other polarity. In this arrangement the danger signal screen will be located between the caution and proceed screens; and when the signal indication is to be changed

from caution to proceed, or vice versa, as is frequently required, the color screen would give a momentary danger signal when moving from one extreme position to its other extreme position. Although such false momentary signals are on the side of safety, in that it is a danger or red signal, the continued recurrence of such false signals, it is believed, would make the engineer unconsciously hesitate in acting upon a danger signal when it first appears, which is of course a dangerous practice, because in some instances, such as approaching a crossover and a similar interfering route, an immediate application of the brakes is essential when a danger signal appears. Further, the engineer, especially if approaching a dangerous place, may make an emergency application of the brakes unnecessarily, when such a momentary false danger signal is given, resulting in the loss of time and useless wear and tear on the railway equipment.

With the above and other considerations in mind, the principal object and purpose of the present invention is to provide means to prevent the momentary flashing of a danger or red signal falsely in color light signals having movable color screens operated by a polarized three-position device; and another object of the invention is to accomplish this end by an arrangement of devices which have established and recognized records of performance, rather than by delicate, complicated and untried devices.

Other objects of the invention will appear as the description progresses, and the novel features thereof will be pointed out in the appended claims.

In describing the invention in detail, reference will be made to the accompanying drawings, in which:—

Fig. 1 is a vertical longitudinal cross section taken through the axis of a typical light signal to which the invention may be applied;

Fig. 2 is a diagrammatic perspective view of the principal operating parts of the device shown in Fig. 1; and

Fig. 3 is a conventional diagrammatic illustration of the operating devices embody-

ing the present invention, and the circuit connections therefor.

The particular signal shown to illustrate the nature of the present invention comprises a casing 1 forming a compartment having a transverse partition 2 therein provided with a small aperture 3. A lens 4 is positioned at one extreme end of the compartment, and a reflector 5 at the other extreme end of the compartment. A lamp 6 with a concentrated filament is located in the focus of the reflector 5, which reflects a large portion of the spherical candle power therefrom so as to focus the light rays in the aperture in the partition 3, from whence these rays are distributed on the lens, which further concentrates or converges them into the desired light beam. Adjacent the partition is a relatively light color screen or spectacle 7 comprising a sector having three color filters or glasses mounted therein to be alternately swung in front of the aperture. These glasses G, R and Y are preferably colored green, red and yellow respectively, thus placing the red in the middle of the sector 7. This sector 7 is riveted to a base member 8, which in turn is pinned to a shaft 9 pivotally supported in socket or jewel bearings 10. The base member 8 is provided with shoulders 11 disposed on opposite sides of the shaft 9. Pivotally mounted on the shaft 9 are two oppositely extending arms 12 normally resting on the shoulders 11 of the base member 8, and having weights 13 integral therewith resting on stationary stops 14. It is obvious that when the shaft 9 is turned in one direction or the other, one of the weighted arms 12 will be raised from its stop 14, thus providing means for biasing the sector 7 to the middle position.

To the shaft 9 is also pinned a gear sector 15, meshing with a pinion 16 on the shaft 17 of a suitable polarized or three-position electro-magnetic device. As shown, this three-position electro-magnetic device is an alternating current relay P of the polyphase induction type having two field windings 18 and 19 and a shell-type rotor 20. The detail construction and operation of a relay of this type is well-known in the art, and for the purpose of obtaining a clear understanding of the present invention, it is sufficient to note that torque is exerted on the rotor to turn it in one direction or the other depending upon the phase relation of the alternating currents in the two field windings; and that this torque ceases when current is cut off from one of these field windings. Thus, by reversing the connections to one field winding, the rotor may be caused to rotate in either direction, and by breaking the electrical connection to this winding, the rotor is free to be moved by the weighted arms 12. For convenience, the position of the rotor and associated parts corresponding to the

deenergized condition of the relay, is termed the middle, intermediate or neutral position, and the positions of the rotor and associated parts corresponding to energization of the relay with different polarities, will be 70 termed normal and reverse.

Pivotedly connected to one corner of the base member 8 is a link 21 having its other end pivotally connected to an arm 22 extending from an insulating block 23 pivotally supported in socket, or jewel bearings 24. On the block 23 are mounted two plates 25 each having parallel knife edges 25', the ends of the knife edges being provided with upstanding lugs 25''. A contact finger 26 is positioned to rest on said knife edges between the lugs of one of the plates 25, and is held yieldingly in this position by a compression coil spring 27, which is held in place by a headed pin passing through the finger and into the insulating block 23. On the other end of the finger 26 is a pair of contact springs 28 riveted thereto to constitute a forked contact member. Stationary adjustable contacts, shown conventionally as arrows, are disposed on opposite sides of the contact springs 28 so as to be engaged thereby when the spectacle 7 is in either of its extreme positions. The two contact springs 28 are spaced apart somewhat farther than ordinarily so as to engage their cooperating stationary contacts, when the block 23 is shifted to a small degree from its middle or neutral position shown in Fig. 2. In other words, the contacts of the finger 26 have what is known as a close adjustment. Another contact finger 29 of the usual form and similar in construction to the one just described, with springs 30, is secured to the block 23 on the other plate 25 and engages stationary contacts shown conventionally as arrows. The circuit connections are established by both of these contact fingers 26 and 29 through a suitable flexible or pig-tail connection 31 to the respective finger and thence through the contact springs 28 or 30 to the stationary contact engaged thereby. It is contemplated that the relay mechanism P, in addition to operating the color screen 7, will in practice also serve as a track or line relay, and for this purpose any desired number of other contact fingers, not shown, will be carried by the block 23.

The operation of the light signal mechanism just described may be outlined briefly as follows. When the relay P is energized with a polarity corresponding to clear or proceed traffic conditions, the rotor 20 drives the gear sector 15 in a clockwise direction, for example, rocking the color screen 7 to bring the green filter G opposite the opening 3, so that the light rays emanating from the lamp 6 and projected from the signal will be colored green. During this movement the lefthand weighted arm 12 is raised,

and when the relay P is deenergized, this weighted arm returns the color screen 7, gear sector 15, and rotor 20 to the neutral position, shown in Fig. 2. When the relay P is energized with the opposite polarity corresponding to cautionary traffic conditions, the gear sector 15 is driven in the opposite direction and rocks the color screen 7 to bring the yellow color filter Y opposite the opening 3, giving a yellow beam of light. In this instance, the right hand weighted arm 12 is raised, and when the relay P is deenergized, returns the parts to their neutral position. As the gear sector 15 and color screen 7 are shifted, the block 23 is rocked in a corresponding direction to close the normal or reverse contacts.

One arrangement of controlling circuits embodying this invention and adapted to be used in connection with the particular type of signal shown in Figs. 1 and 2, is illustrated in a simplified and conventional manner in Fig. 3. In this simplified circuit diagram, the relay P for operating the color screen 7 is shown conventionally as comprising a local field winding 18 and a track or line phase field winding 19. The local field winding 18 is permanently connected to a suitable source of alternating current, shown as a transformer 32, which is of course connected to a suitable transmission line or generator; and the other field winding 19 is connected to the same source of current through a suitable means for reversing its connections. In Fig. 3, a simple pole changing or reversing switch 33 is shown for performing this function, and while this switch may be operated manually, in practice it would ordinarily correspond to contacts of a track or line relay, or circuit controlling means associated with a signal mechanism, these various adaptations and applications being familiar to those skilled in the art.

In accordance with the present invention, a suitable slow releasing relay S is associated with the signal mechanism. This slow releasing relay S may be of any suitable construction, but in the application illustrated, it is shown conventionally as a two-position two-element alternating-current relay of the induction type which is made slow releasing by providing a strong local field acting in the well-known manner to produce a braking of the rotor by the action of eddy currents induced therein, as the rotor is driven by the weighted arms back to its neutral or deenergized position. This local field winding 34 is permanently connected to a suitable source of alternating current, in this instance shown as another transformer 35; and the other field winding 36 of the slow releasing relay S is connected to the same source through the closely adjusted normal and reverse contacts 28 of the relay P. These contacts 28 are shown conventionally

and correspond to the finger 26 and its associated stationary contacts shown in Fig. 2.

The circuit for supplying current to the lamp 6 when the signal indicates clear or caution, and which may be conveniently considered to be the normal lighting circuit, may be traced as follows:—Starting at one terminal of the secondary of transformer 35, wires 37, 38 and 39, lamp 6, wires 40 and 41, through normal or reverse contacts of finger 29 of relay P, wires 42, 43, 44 and 45, back to other terminal of said secondary.

There is an alternative or auxiliary circuit for supplying current to the lamp 6 which includes a shunt for the normal and reverse contacts of the relay P, this shunt including a back contact 46 of the slow releasing relay S. Thus, when the back contact 46 of the slow releasing relay S is closed, the lamp 6 is lighted by a circuit which may be traced as follows:—Starting at transformer 35, wires 37, 38 and 39, lamp 6, wires 40 and 47, back contact 46 of relay S, and wires 48 and 45 back to the transformer.

The operation of the specific embodiment of the invention illustrated, by virtue of which the objectionable "flashing of the red" is obviated, is as follows. Assume the parts and circuits to be in the condition shown in Fig. 3, which corresponds to that existing when the proceed or clear signal is to be displayed. When the switch 33 is shifted to the dotted line position so as to reverse the connections between the source 32 and the field winding 19 of the relay P, the rotor 20 is turned in the opposite direction, and commences the movement of the color screen 7 from its existing extreme position to the other extreme position. As the rotor 20 commences its return movement, contact block 23 is rocked, and sometime before the color screen 7 reaches its middle or neutral position, the finger 29 separates from its normal contact and interrupts the normal lighting circuit, so that as the screen passes through its middle position, the lamp 6 is extinguished, and the red indication is not given. When the relay P assumes its full reverse position, the normal lighting circuit for the lamp 6 is again established at the reverse contact of the finger 29. In this way, the lamp 6 is extinguished while the color screen 7 is passing through its middle position, and consequently, although the red color filter R passes in front of the opening 3, as it must necessarily do in a signal mechanism of this type, the lamp is automatically extinguished at the proper time to avoid the projection of a beam of red light that would give an objectionable though momentary false stop or danger indication.

As the signal mechanism is operated from the normal or proceed position to the reverse or caution position, the energizing circuit for the slow releasing relay S is momentarily

interrupted at the contact finger 26, but on account of the close adjustment of the contacts associated with this finger and the slow releasing properties of this relay, the back contact 46 of this relay is not closed during such a continuous change of the signal mechanism. The operation for a signal change from caution to clear is analogous to that described, and will be evident without detail 10 explanation.

Next assume that the switch 33 is shifted to the middle position, or the field winding 19 of the relay P is otherwise deenergized, this condition corresponding to a stop or 15 danger control. The color screen 7 is now returned to its middle or neutral position by the weighted arm 12, which is raised at that time. During this movement of the signal mechanism, the normal lighting circuit 20 for the lamp 6 is broken at the contact finger 29. Also, the energizing circuit for the slow releasing relay S is broken at the other contact finger 26; and after a short interval of time, the back contact 46 of this slow releasing 25 relay is closed to establish the auxiliary or alternative lighting circuit for the lamp, thereby lighting the lamp to give the desired red or stop indication. The parts are preferably selected and proportioned in practice so 30 that the auxiliary lighting circuit will be established as quickly after the signal mechanism assumes its neutral or deenergized position, as possible to attain, and also be sure with reasonable margins that this auxiliary 35 circuit will not be closed as the signal mechanism changes continuously from one extreme condition to the other.

From the foregoing it will be observed that there is provided by this invention a 40 color light signal in which a movable color screen with the red filter in the middle is operated by a polarized or three-position device, and in which the light is temporarily put out or cut off automatically as the color 45 screen passes through its middle position, so as to avoid "flashing of the red", while at the same time the light is permanently effective to give the desired stop or danger indication when the color screen comes to 50 rest in its middle position. It should be noted that the parts and circuits constituting the invention are organized to comply with the normally closed circuit principle, that is, failure on the side of safety. If the 55 slow releasing relay S fails for any reason, the auxiliary lighting circuit is established, assuring that a stop indication will be given. In other words, the means utilized in this invention to prevent the objectionable "flashing 60 of the red", are such that any failure will not prevent the giving of the red indication when proper to do so. Failure of the back contact 46 of the slow releasing relay S, breakage of wires, or other defects resulting 65 in extinguishing the lamp will of course re-

sult in the absence of any indication, but such a "dark" signal, like all color light signals, works out on the side of safety, since the engineer, having no signal to guide him, will come to a stop or under control, in compliance with the usual rules. 70

While the invention has been shown and described as embodying a signal mechanism of a particular type, and in connection with relays operated by alternating current, it is 75 evident that the same principles and functions may be employed in connection with other similar types of signals and with direct current. Other modifications and adaptations of the specific embodiment of the invention shown and described will be apparent to those skilled in the art, and I desire to have it understood that the particular parts and circuits herein disclosed are merely illustrative of the invention, and do not exhaust 80 the various embodiments of the invention that may be made and used in a practical manner. 85

What I claim is:—

1. In a light signal, an incandescent lamp 90 and an optical device for projecting light from said lamp, a member comprising a plurality of color screens, means mounting said member for movement to an intermediate and two extreme positions to thereby interpose one of said screens in the path of the light, and means for extinguishing said lamp when said member is moved from one of its extreme positions to the other. 95

2. In a light signal, a light source and an 100 optical device for projecting light from said source, a member comprising a plurality of color screens, means mounting said member for movement to an intermediate and two extreme positions to thereby interpose one of said screens in the path of the light, said 105 color screens allowing the emission of a light beam of different color for each of said positions, and means for extinguishing said light source when said member is moved continuously from one extreme position to the other and for illuminating said source when said member comes to rest in its intermediate position. 110

3. In a light signal, an incandescent lamp 115 having an energizing circuit and an optical device for projecting light from said lamp, a member comprising a plurality of color screens, means mounting said member for movement to an intermediate and two extreme positions to thereby interpose one of said screens in the path of the light, said member being biased to said intermediate position and said color screens allowing the emission of a light beam of different color 120 for each of said positions, circuit controlling means and means for operating said circuit controlling means synchronously with the movement of said member for temporarily interrupting said energizing circuit for said 125 130

lamp as said member is moved from one of said extreme positions to the other.

4. In a light signal, an incandescent lamp having an energizing circuit and an optical device for projecting light from said lamp, a member comprising a plurality of color screens, means mounting said member for movement to an intermediate and two extreme positions to thereby interpose one of said screens in the path of the light, said member being biased to said intermediate position, a three-position electro-magnetic device for moving said member and means for interrupting said energizing circuit for said lamp as said member moves through said intermediate position.

5. In a light signal, an incandescent lamp having a first lighting circuit and an optical device for projecting light from said lamp, a second lighting circuit for the lamp, a member comprising a plurality of color screens, means mounting said member for movement to an intermediate and two extreme positions to thereby interpose one of said screens in the path of said light, means for interrupting said fixed lighting circuit when said member is in said intermediate position and independent means for closing said lighting circuit through the lamp when said second member is at rest in said intermediate position.

6. In a light signal, an incandescent lamp and an optical device for projecting light from said lamp, a member comprising a plurality of color screens, means mounting said member for movement to an intermediate and two extreme positions to thereby interpose one of said screens in the path of the light, an energizing circuit for said lamp, means for interrupting said energizing circuit through said lamp when said member is in its intermediate position, and slow-acting means for closing another circuit through said lamp after said member remains at rest in its intermediate position for an interval of time.

7. In a light signal, an incandescent lamp and an optical device for projecting light from said lamp, a member comprising a plurality of color screens, means mounting said member for movement to an intermediate and two extreme positions to thereby interpose one of said screens in the path of the light, an energizing circuit for said lamp, a three-position electro-magnetic device for controlling the movement of said member to said positions, and slow-acting means controlled by said electro-magnetic device for controlling said energizing circuit for said lamp.

8. In a light signal, an incandescent lamp and an optical device for projecting light from said lamp, a member comprising a plurality of color screens, means mounting said member for movement to an intermediate

and two extreme positions to thereby interpose one of said screens in the path of the light, an electro-responsive device for operating said member to said positions, a circuit controlling means operated by said electro-responsive device for closing an energizing circuit through said lamp only when said member is in said extreme positions, an auxiliary circuit for supplying energy to said lamp and means including a slow-acting device rendered effective when the electro-responsive device has assumed its intermediate position for establishing the auxiliary circuit after an interval of delay.

9. In a light signal, an incandescent lamp and an optical device for projecting light from said lamp, a member comprising a plurality of color screens, means mounting said member for movement to an intermediate and two extreme positions to thereby interpose one of said screens in the path of the light, an electro-responsive device for operating said member to said positions, a normally open energizing circuit including said lamp and slow-acting means for closing said circuit, said slow-acting means being governed by said device and having its operation initiated when said device operates said member to its intermediate position.

10. In a light signal, an incandescent lamp and an optical device for projecting light from said lamp, a member comprising a plurality of color screens, means mounting said member for movement to an intermediate and two extreme positions to thereby interpose one of said screens in the path of the light, a three-position electro-magnetic device for operating said member, an energizing circuit for said lamp, means for closing said circuit only when said device moves said member to one or the other of its extreme positions, a second energizing circuit for said lamp, a slow-acting relay having a back contact controlling said second energizing circuit, an energizing circuit for said slow-acting relay, and means for closing said last mentioned circuit only when said device moves said member to one or the other of its extreme positions.

11. In a light signal, an incandescent lamp and an optical device for projecting light from said lamp, a member comprising a plurality of color screens, means mounting said member for movement to an intermediate and two extreme positions to thereby interpose one of said screens in the path of the light, said member being biased to said intermediate position, an energizing circuit for said lamp, an alternating current relay for operating said member and for opening said energizing circuit when said member is in its intermediate position, a slow-releasing alternating current relay energized and de-energized respectively, as said member assumes either extreme position or its in-

termediate position, and another energizing circuit for said lamp including a back contact of said slow-releasing relay.

12. In a three-indication color light signal, the combination with a three-position relay governing the indications of said signal, a light circuit for the signal including normal and reverse contacts of said relay, a

slow releasing relay having an energizing circuit including normal and reverse contacts of the first mentioned relay, and an auxiliary circuit for said lamp including a back contact of the slow releasing relay.

In testimony whereof I hereto affix my signature.

PAUL E. CARTER.
